UNITED STATES PATENT OFFICE.

CHARLES L. MARSH, OF BRIDgewater, SOUTH DAKOTA.

DOOR-OPERATING DEVICE.

Application filed October 22, 1921. Serial No. 509,510.

To all whom it may concern:

Be it known that I, CHARLES L. MARSH, a citizen of the United States, and resident of Bridgewater, in the county of McCook and State of South Dakota, have invented new and Improved Door-Operating Devices, of which the following is a full, clear, and exact description.

My invention relates to an improved door operating device therefor, which apparatus is particularly adapted for use in connection with garages, etc.

In connection with garage doors, it is a well appreciated fact that considerable objection has been noted, incident to the fact that in most structures of this nature, an operator of a vehicle has been compelled to alight to open the doors, and to subsequently alight after passing through the doors, so as to close the panels of the same.

Certain structures have been proposed which include a motor for operating the doors in a more or less automatic manner, but these devices for the most part have proven extremely impractical, incident to the cost of installation and maintenance, aside from the fact, that due to their relatively complicated construction, danger has always existed that the parts would become jammed, or damaged in such a manner that the apparatus would cease to function.

With this in mind my present invention aims to provide a door operating device by means of which an operator will be able to cause an actuation of the parts of the same without alighting from the vehicle which he is operating, and will further operate in such a manner that upon the approach of the vehicle, the operator may cause the doors to be automatically opened, these doors being subsequently closed after the vehicle has passed through the door-way.

Another object of my invention is the provision of a novel construction of door and operating means thereof, which shall be extremely simple in the arrangement of its parts, so that the same may be installed at an extremely nominal figure, aside from the fact that practically no fear may be felt that the parts will refuse to function.

Still another object of this invention is the provision of a device of the character stated in which the operating means preferably relies upon the movement of the vehicle to effect an actuation of the parts thus over-

coming the difficulty incident to the use of an extraneous motor, complication of parts, etc.

Further objects of this invention will become apparent in the annexed specification 60 taken in connection with the drawings, which latter illustrate one practical embodiment of the same and in which:

Figure 1 is a front elevation of a door and approach therefor embodying my improved construction.

Figure 2 is a rear view of the same.

Figure 3 is a sectional plan view taken along the line 3—3 and in the direction of the arrows indicated in Figure 1. 70

Figure 4 is a partly sectional side elevation taken along the line 4—4 and in the direction of the arrows indicated also in Figure 1, and

Figure 5 is a somewhat diagrammatic 75 perspective view of a certain detail of the operating mechanism.

It will be seen in Figures 1 to 4 that the reference numeral 10 indicates a surface constituting a drive-way which drive-way 80 has a door frame 11, of any suitable construction extending above its surface. Also a supporting rail 12 extends above the door-way opening, and is supported by the frame 11, and panels 13 are provided which serve 85 to normally close the door-way opening.

Contrary to the conventional construction, however, it will be seen that these panels 13 are each preferably provided with but a single hanger 14, which latter co-operates 90 with a supporting rail 12, thus suspending each panel adjacent its upper and inner edge.

With a view of properly supporting the balance of the body, of each panel, it will 95 be seen, attention being invited to Figure 2, that I preferably employ U-shaped members 14 for each panel, the body of these U-shaped members being rotatably supported by brackets 15 fixed to the frame 11, the 100 arms 16 of these members extending inwardly and having their ends attached to brackets 17 affixed to the inner faces of the panels 13, and at points preferably intermediate the side edges thereof. 105

Thus as in Figure 3 the panels 13 are normally swung to a position at which their inner edges lie in a single plane. However upon the members 14 being swung forwardly and outwardly the panels will move 110

to the position indicated in dotted lines in Figure 3, it being noted that incident to the connection existing between the hangers 14 and the rail 12, that the inner edges of the 5 panels will remain in line with the door-way. Upon this swinging movement being continued, it will be seen that the panels 13 will move to the extreme position indicated in dotted lines in Figure 3, i. e., to a position 10 at which the bodies of the panels will extend at right angles to the opening of the door-frame.

Now with a view of providing means which will serve to effect this actuation, it 15 will be noted, reference being had to Figures 2 and 5, that each of the members 14 has rigidly attached to its body an arm 18, and to one of these arms, the ends of cables 19 and 20 are secured, the second arm having 20 attached to it the ends of cables 21 and 22. A pair of main cables or flexible elements 23 and 24 are provided, the former having its inner end terminating in the cable 19, and also having the cable 22 secured in 25 advance of this end portion. Both of the cables or flexible members 19 and 22 pass over suitable pulleys 25, and the said cable 22 as aforesaid, is secured to the arm 18 of the second member 14. The cable or 30 flexible member 24 passes around a pulley 26 and terminates in the cable 21 aforesaid, it being noted in this connection that the cable 20 is attached to the body of the cable 24 short of its end portion 21.

Assuming that a pull is exerted upon the cable 24 it will be seen that this will result 35 immediately in the cables 21 and 20 becoming tensioned, and upon this pull being continued it will be obvious that the members 14 and arms carried thereby will be moved to the position indicated in full lines in Figure 5, to the position indicated in dotted lines in this figure. The movement in an opposite direction on the part of the 40 panels may be subsequently effected by a pull upon the cable 23, which will in turn cause a tension to be imparted to the cable 19 and the cable 20. The pull upon the former will cause the member 14 and the 45 panel carried thereby to be swung to its closed position and the pull upon the latter will cause a similar action on the part of the second panel by virtue of the fact that this 50 cable is connected to the arm 18 of the second member 14.

Finally to provide means which will 55 result in the operation aforesaid, it will be noted, attention being invited to Figure 4, that the cable 24 has its outer end split into two portions 24' and 24'' these 60 portions extending in opposite directions

along the drive-way 10 and being connected to rocking striker members 27. In a similar manner the cable 23 is divided into two portions extending in opposite directions 65 from the door-way 11, and being also connected to striker members 27 situated adjacent the opposite side edges of the drive-way.

Thus it will be obvious that a vehicle may 70 roll up to one of the striker members 27 and engage the same with its forward wheel. This will result in a pull being exerted either upon the cable 23 or cable 24 and as the vehicle advances the same will ride over 75 the striker member, the latter being depressed to a position at which it will offer virtually no obstruction of this passage. This pull will cause the operation of the 80 panels aforesaid, and upon the operator reaching the opposite side of the door-way a similar engagement between one of the striker members of the second set and the front wheel of the vehicle will cause the doors to close again.

Obviously numerous modifications of 85 structure might readily be resorted to without departing from the spirit of my invention, which I claim as:

A door and door-operating structure, including the combination of a doorway, a door including a pair of oppositely movable panels, means for supporting and guiding said panels for movement towards each other to closing position to lie in the same 90 vertical plane and away from each other to open position to lie in spaced vertical planes substantially perpendicular to the plane of the doorway; said means including a horizontal overhead fixed track, and a track-guided member fixed on each panel, a C-shaped member for each panel vertically pivoted at an intermediate portion of the member near a side of the doorway and having terminal portions pivoted 95 connected to each panel intermediate the top and bottom of the latter, each C-shaped member having a fixed arm projecting therefrom at an angle to the plane of the C; there being also provided a system of cables 100 and pulleys for opening and closing both panels simultaneously; said system including cable elements running in opposite directions across the plane of the door away from each arm, and a plurality of additional cable 105 elements operatively connected to the cable elements first-mentioned and one of which may be manually pulled when the panels are open to close the latter and the other of which may be manually pulled when the 110 panels are closed to open said panels.

CHARLES L. MARSH.
